[57] CLAIM

The ornamental design for an extended faucet, as shown and described.

DESCRIPTION

FIG. 1 is a perspective view taken from the top, front and left side of an extended faucet showing my new design;

FIG. 2 is a front elevational view thereof;

FIG. 3 is a right side elevational view thereof; and,

FIG. 4 is a top plan view thereof.

The broken line representation of a faucet and the fragmentary broken line representation of a building side in FIG. 3 are for purposes of illustration only and form no part of the claimed design.
